UNITED STATES PATENT OFFICE.

JESSE PETER SPENCER, OF FROST, TEXAS.

DESIGN FOR A WATER-GRADE FOR COOKING-STOVES.

SPECIFICATION forming part of Design No. 31,011, dated June 13, 1899.

Application filed May 18, 1899. Serial No. 717,368. Term of patent 14 years.

To all whom it may concern:

Be it known that I, JESSE PETER SPENCER, a citizen of the United States, residing at Frost, in the county of Navarro and State of Texas, have invented and produced a new and original Design for a Water-Grate for Cooking-Stoves, of which the following is a specification.

The invention relates to a new and original design for water-grates for cooking-stoves.

The essential feature of the invention resides in a water-grate for cooking-stoves having a bottom and front composed of parallel transverse portions and connecting U-shaped portions. A minor feature of the design resides in the side tubes having a vertical rear arm at one side of the grate and provided at the opposite side with a pair of vertical arms and a connecting horizontal portion.

In the drawings, Figure 1 is a perspective view of a water-grate for cooking-stoves, showing my new and original design. Fig. 2 is a front elevation of the same.

Like numerals of reference designate corresponding parts in both figures of the drawings.

1 designates a water-grate having its bottom 2 and front 3 composed of parallel trans-

verse tubes connected at their ends by alternately-arranged U-shaped portions or couplings 4. One of the side tubes 5 and 6 is provided with a vertical arm 7, located at the back of the grate and extending from the rear transverse tube 8 to the side tube 5. The other side tube 6 is provided with parallel arms 9 and 10 and a horizontal portion 11, located at the bottom of the grate and connecting the lower ends of the arms 9 and 10. The arm 9, which is arranged in the same plane as the front of the grate, extends from the top transverse bar 12 to the horizontal part 11, and the other vertical arm 10, which is located at the back of the grate, extends from the portion 11 to the side tube 6.

What is claimed is—

The design for a water-grate herein shown and described.

In testimony that I claim the foregoing as my own I have hereto affixed my signature in the presence of two witnesses.

JESSE PETER SPENCER.
